GASOLINE PUMP

Duncan McRae, White Lake, Mich., assignor to John
Wood Company, New York, N.Y., a corporation of
Delaware

Filed June 2, 1964, Ser. No. 80,245

Term of patent 14 years

(Cl. D52—2)

FIG. 1

FIG. 1 is a front elevation of a gasoline pump embodying my new design.

FIG. 2 is an end view of the gasoline pump shown in FIG. 1.

FIG. 3 is a rear elevation of the gasoline pump shown in FIG. 1.

The undisclosed other end of the gasoline pump is the same as that shown in FIG. 2. The dominant features of my design reside in the portions shown in the drawings in full lines.

I claim:

The ornamental design for a gasoline pump, as shown and described.
